UNITED STATES PATENT OFFICE.

SAMUEL N. ELLENWOOD, OF JONES, OKLAHOMA.

CAR-REPLACER.

No. 900,838.

Specification of Letters Patent.

Patented Oct. 13, 1908.

Application filed April 20, 1908. Serial No. 428,231.

To all whom it may concern:

Be it known that I, SAMUEL N. ELLENWOOD, a citizen of the United States, residing at Jones city, in the county of Oklahoma and State of Oklahoma, have invented certain new and useful Improvements in Car-Replacers, of which the following is a full, clear, and exact description, reference being had to the accompanying drawings.

Many devices for placing derailed cars onto the track are in use, and these devices consist commonly of two separate members of frogs which are laid upon the cross-ties or road-bed by the side of the track-rails, so that the car may be drawn forward onto said frogs and led forward and upward into a position to alight from said frogs onto the track-rails. One disadvantage in the use of these appliances is that the frog used on the outside of the rail must rest on the ends of the cross-ties of the track, in place of resting upon a firmer and more central point between the track rails, and since the car is usually pitched or inclined in the direction of its derailment the heavy load is brought upon this frog, thus often breaking down the ends of decayed cross-ties and leaving the car in a still worse stage of derailment. Another disadvantage is that one or both of the frogs will slide forward along the track when the car trucks are drawn upon or against them, thus failing in their purpose, racking the truck frame, and injuring the cross-ties and ballast of the road-bed.

The object, therefore, of the present invention is to overcome the disadvantages above named.

Other objects and advantages of the invention will be set forth in the ensuing description.

Referring to the accompanying two sheets of drawings: Figure 1 is a plan view of a rail-way track, showing a derailed car-truck, and the improved appliance in position for use. Fig. 2 is an enlarged sectional view, taken on the line 2—2 of Fig. 1. Fig. 3 is an enlarged sectional view, taken on the line 3—3 of Fig. 1. Fig. 4 is a sectional view, taken on the line 4—4 of Fig. 1, said Fig. 4 being on a scale smaller than Figs. 2 and 3 and larger than Fig. 1. Figs. 5, 6, and 7 are views of separate parts of the appliance.

Referring to the several figures, in all of which like characters of reference designate like parts, the improved device comprises two rails T and N, the rail T being shown in

side elevation in Fig. 6, the rail N in side elevation in Fig. 7.

In setting the parts of the device into position for use, the rail T is used between the track rails P and P^b, and its front or wider end is clamped against the inside of the rail P by a screw clamp X, as shown in Figs. 1 and 3.

The surface of the rail member T which contacts with the rail P is curved, as at H, to allow adjustment of the angular relation between said parts. The other rail member N is likewise clamped to the opposite track rail P^b, said rail member N lying on the outside of said track rail P^b as shown in Figs. 1 and 2. After thus arranging and securing the two rails T and N into place, their rear or free ends are swung into proper position to receive the derailed trucks B, as shown in Fig. 1, and said trucks are drawn forward onto said rails T and N in the same manner that they have heretofore been drawn up onto the common replacing frogs.

In order to bring the flange of the outer derailed truck B over the rail P^b onto the inside thereof, the front end of the rail N is provided with a hook or lip J which laps onto and in fact hooks over said rail P^b as best shown in Figs. 1 and 2, and when said flange B of said truck comes in contact with said lip it rolls up onto the same in such position that when rolling on thereover it alights upon said rail P^b in position to slide into proper place on the inside thereof.

In case the derailment is on the opposite side of the track, the rails T and N are placed on the opposite sides of their respective track rails, the rail member N being placed over onto the inside of the track rail P^b, and the rail member T over onto the outside of the track rail P.

In order to reverse the rails T and N as just described, the upper and lower faces of the rail T are both shaped for track faces, so that said rail may be placed with either face up, as necessary in reversing it from one side to the other.

Since the rail N is provided with the lip J, as aforesaid, and since it would therefore be impractical to form this rail so that it could be turned with the lower face upward and properly attach to track rails of the present form, said rail N is provided with lips J on both edges, so that it may lie upon either side of a track rail and hook onto the same without being turned upside down.

To hold the rails T and N parallel with each other and maintain a distance of proper track gage between them, the rear or free ends of said rails are connected together by 5 a cross-bar U, the rail T lying between and being retained by studs F and D on said cross-bar, while the rail N is likewise retained in position by similar studs K and M.

In order to provide better support for the 10 outer rail N than is afforded by resting upon the outer ends of the cross-ties W, the cross-bar U does not pass under the track rails P^b, but lies upon the top of said rail as shown in Figs. 1 and 4, said cross-bar being suitably 15 arched so as to bring the rail member N to proper working level. It will be noted, however, that the end of the cross-bar U supporting the rail T passes under the opposite track rail P, so that it is held downward by 20 said track rail P against the heavy load that is brought upon the rail N on the side of the track at which the car is derailed.

In order that the cross-bar U may slide laterally of the railway track and allow adjustment of position on the rear or free ends of the rails T and N, the arched portion G of 25 said cross-bar is elongated, and in order that said cross-bar may be locked against movement toward the side of the track upon which 30 the derailment has occurred when the trucks G are drawn against or upon the rails T and N, said cross-bar U is provided with a series of holes Q so that a pin L may be driven down therethrough into the road-bed on the out- 35 side of the track rail P, as best shown in Fig. 4.

The foregoing being a full, clear, and exact description of the invention, what I claim and desire to secure by Letters Patent is:

1. In a car-replacer, a rail member adapted 40 to have one of its ends secured in contact with the inner side of a track-rail, a second rail member adapted to have one of its ends secured in contact with the outer side of the opposite track-rail, a bar connecting the free 45 ends of said rail members for holding them

spaced for proper track gage, said bar passing over and resting upon said opposite track-rail and extending under said first-named track-rail.

2. In a car-replacer, a rail member adapted 50 to have one of its ends attached to the inner surface of a track-rail, a second rail member adapted to have one of its ends attached to the outer surface of the opposite track-rail, a bar connecting the free ends of said rail members 55 and holding them spaced to proper track gage, said bar being adapted to pass over and rest upon said opposite track-rail and extend under said first-named track-rail, and a pin adapted to pass down through said bar and 60 into the road-bed to prevent said bar and the rail members connected thereby from moving laterally of the track.

3. In a car-replacer, a rail member adapted 65 to be clamped against the inner surface of a track-rail and have one of its ends extend into position to receive a derailed truck, a second rail member adapted to be clamped against the outside surface of the opposite track-rail and have one of its ends extend into position 70 to receive a derailed truck, the second-named rail member having a hooked extension adapted to hook over the upper or ball portion of said opposite rail, clamps for securing said rail members to said track-rails, a bar connecting and supporting the free or extending 75 ends of the rail members, said bar passing over and resting upon said opposite track-rail and extending under said first-named track-rail, a pin adapted to pass down through 80 said bar on the outside of the first-named track-rail to prevent said bar and the rail members from swinging in the direction of derailment of the car trucks.

Witness my hand this 25 day of March, 85 1908.

SAMUEL N. ELLENWOOD.
